UNITED STATES PATENT OFFICE.

HENRY L. PIXLEY, OF CLEVELAND, OHIO.

GRINDING DEVICE FOR MACHINE-TOOLS.

1,074,739

Specification of Letters Patent.

Patented Oct. 7, 1913.

Application filed December 9, 1912. Serial No. 735,825.

To all whom it may concern:

Be it known that I, HENRY L. PIXLEY, a citizen of the United States, residing at Cleveland, in the county of Cuyahoga and 5 State of Ohio, have invented certain new and useful Improvements in Grinding Devices for Machine-Tools, of which the following is a specification.

This invention relates to a grinding device 10 for machine tools, and the invention consists in a device more especially constructed and arranged as herein shown for sharpening planer knives.

In the accompanying drawings, Figure 1 15 is a side elevation of my new and original attachment, broken out at one end and shown in working relation on a machine shaft and to the cutter blades thereon. Fig. 2 is an end elevation showing the means of support 20 for the attachment upon the machine shaft, and Fig. 3 is a substantially similar elevation showing the support at the other end and the motor chamber and grinder in that connection. Fig. 4 is a plan view of a portion of Fig. 2 omitting the motor chamber 25 except a fragment.

It will of course be understood that the device thus shown is a complete and separate article of manufacture as such and independent of the tool carrying shaft *s* and the knives or blades *b* supported thereon and to which the attachment is brought to do the sharpening without removing the knives. The said device or attachment consists, first, 30 of a frame of peculiar and original construction adapted to carry the operating parts including the grinder *g*, and the said frame comprises rigid parallel guide bars 2 one above the other and provided each with 35 a rabbet lengthwise inside on their top as seen in cross section, Fig. 3, and serving as guide-ways for the body or head 4 which carries the motor chamber *c* and the grinder *g* suspended therefrom on the motor shaft. 40 The formation of these latter parts is further seen in Fig. 4 in which the said body 4 is shown in plan or edge view and is provided on its face with vertically disposed 45 under cut or beveled lugs or ribs 5 adapted 50 to serve as guide-ways for the vertically disposed hanger *h* having beveled edges confined in said guide-ways to slide up and down under adjustment by hand controlled screw 6 engaged through the right-angled 55 head of said hanger and having its bearing in the body 4 as seen at 8, whereby the

motor chamber is adapted to be raised and lowered and the grinder therewith as presently seen.

The motor inclosure or chamber *c* is pivotally supported upon or from the hanger *h* on a pivot screw or pin 10 above the middle of the said chamber and is adapted to swing upon said pivot within limits fixed by opposite screws 12 through said lugs or guides 5 on the back of body 4, according to the position desired for the grinder, as seen in full and dotted lines, Fig. 2. The said grinder is mounted directly upon the motor shaft 14, or an extension thereof, and the 60 said motor is preferably of the electrical type and carried in said chamber. Handles 15 are provided at the top of the motor chamber which are adapted to swing the motor on its pivot as above described and 65 according to the grinding action that may for the time be desired upon the blade *b*. That is it serves to determine whether the grinding shall be at one inclination or another across the blade, as seen in Fig. 3. 70 Now, the means for securing the said frame with its parallel bars 2 and the supporting posts or pieces *m* and *n* upon the machine are seen clearly in Figs. 2 and 3, and in the case of the post *m* it will be seen that 75 the said post is curved to a substantially right angle in its lower portion and is provided with an over reaching arm 17 on its top and end and a bore through its main portion opposite said arm to receive the 80 shank 24 of the forked bearing member *o*. The said bearing or bearing member *o* has, the ends of its forks spread laterally to be 85 engaged by screws 20 to the bearing block or base 21 for machine shaft *s*, and the 90 crotch of said forked member rests directly upon said shaft. This brings the said support or post *m* into direct or immediate touch with the shaft which carries the 95 blades to be ground and eliminates all intermediate mechanism as heretofore employed and through which it seemed impossible to get uniformity of grinding the full length of the blades. Set screws 22 and 23 engage the shank 24 of said bearing member 100 *o* and serve to make refined adjustments and to rigidly fix said parts together. The 105 grinder is supported slidably back and forth on the said frame bars 2 through the head or body 4 and the motor chamber is responsive to the close adjustments obtained through said screws 22 and 23 at that end 110

of the attachment while the other end is supported by post *n* directly upon the pulley 25 upon the corresponding end of shaft *s*. The said post or support *n* likewise is curved 5 to a right angle and is provided with a separable bearing member 26 at its bottom engaged on said pulley and thus this end of the attachment also is brought into practical engagement with shaft *s* and where the 10 support for the attachment cannot deviate when the engagement has been properly made and adjusted.

Obviously, when sharpening of the knives or blades *b* is in progress the shaft *s* is stationary, and the grinder *g* alone is revolved, and this also presupposes the bringing of the knives into exact relations with the grinder so as to cut at the right bevel or angle, certain latitude of movement of the 15 20 grinder being however allowed as the sharpening proceeds, as is seen in the spring provided for by set screws 12, Fig. 4, and as shown in dotted lines, Fig. 1.

The pulley 25 is provided with graduated marks or lines 30 at certain points agreeing with the adjustments to be made to bring the blades in right relations to the grinder for sharpening, and a set 32 is fixed in the support *n* and has a right angled indicating point adapted to register with a given mark 30 and thus accurately give the right rotation to shaft *s* to bring a knife under the grinder *g*.

Presumably the operation will be clearly understood from the foregoing description and need not be further described. I might of course have substantially the same or a similar construction of support *n* to the support *m* and thus cause direct engagement of 35 40 the attachment at both bearings upon shaft *s* instead of having indirect engagement through pulley 25 as the present construction shows and either arrangement is the equivalent of the other and may be adopted. 45 The said pulley being rigid on the shaft and perfectly true in its periphery, it serves the same end as to accuracy of bearing as is shown by standard or post *m*, and the only practical difference is to engage over the 50 pulley instead of over the shaft but both engagements are upon the same axis or the axis of the said shaft though in one case the solid pulley 25 bridges the difference.

Springs 33 are interposed between set

screws 12 and the swinging support 7 of the 55 motor chamber adapted to normally bear against the same and hold the said chamber in working position.

The device is easily applied to any planer without loss of time or labor and with the 60 certainty that all the knives will be governed alike and uniformly from end to end.

What I claim is:

1. An attachment for sharpening planer knives and the like having a suitable frame, 65 a rotatable grinder movable lengthwise on said frame as grinding proceeds, means by which said frame is mounted directly upon the shaft carrying the blades to be sharpened, a motor pivotally supported by said 70 frame and means operatively connecting said grinder with said motor.

2. An attachment carrying a grinder adapted to sharpen planer knives consisting of a frame having parallel horizontal bars 75 and standards carrying said bars curved inward at substantially right angles at their lower ends and means on said ends constructed to support said frame directly upon the axis of the knives to be sharpened, in combination with a head slidably mounted on said parallel bars, a motor chamber pivotally mounted on said head, a motor in said chamber having a downwardly projecting shaft, a grinder operatively connected 85 with the end of the said shaft and means adjustably supporting said motor chamber on its pivot.

3. A grinder attachment for planer knives comprising a frame having uprights adapted to rest upon the axis of said knives and parallel horizontal guide-bars supported on said uprights, a head slidably mounted on said bars, a hanger supported at the upper portion of said head and guide-ways therefor on the front of said head and a screw to adjust said hanger on said head, in combination with a motor chamber and motor pivoted on said hanger and means to adjust said hanger laterally in its lower portion 100 comprising springs on each side.

In testimony whereof I affix my signature in presence of two witnesses.

HENRY L. PIXLEY.
